George Morgan,
INVENTOR

BY *Victor J. Evans*,
ATTORNEY

WITNESS:

William Thompson

UNITED STATES PATENT OFFICE

GEORGE MORGAN, OF BINGHAMTON, NEW YORK

HOLDER

Application filed November 7, 1928. Serial No. 317,801.

This invention relates to spring clips for removably attaching cards, tags and like articles, the invention being especially adapted for attaching information cards to containers used in shoe factories when carrying goods from one department to another.

Another object of the invention is the provision of a clip by means of which a card may be inserted either sidewise, or endwise, or from beneath or above the clip, so as to save time in attaching the cards.

Another object of the invention is the provision of a clip which is constructed from a single length of material and shaped to provide the advantageous features above noted, and in addition, provide a spring tongue which bears upon the clip.

With the above and other objects in view, the invention further includes the following novel features and details of construction, to be hereinafter more fully described, illustrated in the accompanying drawings and pointed out in the appended claims.

In the drawings:

Figure 1 is a perspective view illustrating the invention in use.

Figure 2 is a longitudinal sectional view showing the position of the holder when not in use, a portion of a container being illustrated by broken lines.

Figure 3 is a perspective view showing a slightly different form of the invention.

Referring to the drawings in detail where like characters of reference denote corresponding parts, the reference character 10 indicates the base of the holder which is constructed of a single length of spring metal. The base is turned obliquely at one end as indicated at 11 and bent upon itself and extended inward to provide an arm 12. This arm is parallel with the base 10 and its inner end is bent outward to provide a retaining tongue 13 which engages the arm 12 and the inner portion 14 of said tongue is spaced from the arm and provides an entrance 15. The end of a card may be inserted through this entrance and held between said arm 12 and the intermediate portion of the tongue. A card may also be inserted sidewise from the end of the clip and for this purpose, the

extremity of the tongue is curved outward as shown at 16 and cooperates with the offset portion 11 to provide a card entrance 17.

The opposite end of the base 10 has extending therefrom a spring reinforcing tongue 18 which is formed by bending the material upon itself as shown in the drawings. The free end of the tongue 18 extends over the inner portion 14 of the tongue 13 and provides an auxiliary spring.

The device just described and shown in Figures 1 and 2 of the drawings is especially designed to be placed upon a box or container and may be attached to the inside of the box near the upper open edge of the latter. When not in use, the holder is turned downward within the box as indicated in Figure 2 and when in use is swung pivotally upward and retained in upstanding position by means of a fastening device 19, the holder being permanently attached to a container or other support 20 by a screw or fastening device 21.

In Figure 3, the holder is formed from a single piece of resilient material and comprises a base 22 which is bent upon itself to form an arm. This arm includes a straight portion 23 parallel with and yieldingly engaging the base, and an offset or loop portion 24. This latter portion together with the base provides a card entrance opening 25 to permit of the insertion of the end of a card. The arm has extending from the opposite end of the straight portion 23, an outwardly curved extremity 26, while the adjacent end of the base 22 is provided with a rightangled flange 27. This flange is provided with openings 28 for the passage of fastening devices to permit the clip to be secured in position. A card may also be inserted between the base and flat portion 23 of the arm through the entrance formed by the outwardly curved extremity 26 and the flanged end of the base.

This invention is susceptible of various changes in its form, proportions and minor details of construction and the right is herein reserved to make such changes as properly fall within the scope of the appended claims.

Having described the invention what is claimed is:

1. A clip formed from a single length of re-

silient metal shaped to provide a flat base having an oblique portion at one end, said base being bent upon itself at its oblique end to provide an arm disposed parallel with the outer face of the base, a retaining tongue extending from the inner end of the arm, said tongue having its intermediate portion engaging the outer face of the arm and its inner portion spaced from said arm to provide for the entrance of a card, an outwardly curved extremity at the outer end of the tongue defining with the portion of said arm adjacent said oblique portion, a card entrance and means to attach the opposite end of the base to a support.

2. A clip formed from a single length of resilient metal shaped to provide a flat base, said base being bent upon itself at one end to provide an arm disposed parallel with the outer face of the base, a retaining tongue extending from the inner end of the arm, said tongue having a portion spaced from said arm to provide for the entrance of a card, an outwardly curved extremity at the outer end of the tongue defining with the portion of said arm adjacent to the first mentioned end, a card entrance and a resilient reinforcing spring tongue extending from the other end of the base and having its free end engaging over the first mentioned tongue.

In testimony whereof I affix my signature.
GEORGE MORGAN.
